ELECTROCARDIOGRAM RULER

Horace E. Allen, Toledo, Ohio, assignor to A. H. Robins Company, Incorporated, Richmond, Va., a corporation of Virginia

Filed Jan. 5, 1965, Ser. No. 83,278

Term of patent 14 years

(Cl. 83—1)

Fig. 1

Fig. 2

FIGURE 1 is a top plan view of a ruler embodying the novel design of this invention, and FIGURE 2 is a front elevation view thereof.

The undisclosed bottom portion of the ruler is substantially plane and unornamented.

I claim:

The ornamental design for an electrocardiogram ruler, substantially as shown and described.
